(57) **CLAIM**

The ornamental design for a connector for an insufflation circuit, as shown and described.

DESCRIPTION

FIG. 1 is a top, front and right side perspective view of the connector for an insufflation circuit embodying our new design.

FIG. 2 is a bottom, rear and left side perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side view thereof.

Where utilized, dash-dash broken lines are used to illustrate features of the respiratory circuit that form no part of the claimed design.

1 Claim, 4 Drawing Sheets
